UNITED STATES PATENT OFFICE.

ROY D. FOULKE, OF WARSAW, INDIANA, ASSIGNOR TO WINIFRED DE PUY, OF WARSAW, INDIANA.

SURGICAL SPLINT.

Application filed March 12, 1923. Serial No. 624,432.

This invention relates to improvements in surgical splints especially of that class used for holding in fixed position fractured bones that have been reset and which require an expedient for obviating interference from abducent muscles during the healing process. The object of the improvement is to provide an appliance of its class that will admit of ready adjustment to the body of a patient so as to sustain the arm relative to the body in such fixed relation thereto as may be determined by the surgeon to insure the greatest comfort possible to the patient. Another object is to afford a construction that when applied to the patient it will be retained in the particular position to which it was adjusted.

These objects are accomplished by the construction illustrated in the accompanying drawings, in which:—

Fig. 1 is a side elevation of a construction embodying the invention; and

Fig. 2 is a plan view projected from Fig. 1. The characters appearing in the description refer to parts shown in the drawings and designated thereon by corresponding characters.

The invention comprises a frame consisting of an anchor bar 1 and a supporting bar 2 that are connected by means of a pivot 3 at their corresponding ends. Also, upon the pivot 3 is secured a threaded rod 4 that extends through a toggle mechanism consisting of a link 5 and pivoted arms 6 extending therefrom, the arms being also connected respectively with the anchor bar 1 and the supporting bar 2 by means of corresponding clips 7. The rod 4 has thereon a nut 8 that bears against one side of the link, and a thumb-nut 9 that bears against the opposite side of the link, so that the toggle mechanism may be positioned relative to the rod at such points as to sustain the supporting bar 2 at such angle relative to the anchor bar as may be desired.

Upon the upper part of the anchor bar 1 is fixedly secured a trunk rest consisting of a curved plate 10 that is lined upon its concave face with a pad 11 of felting or other suitable material.

On each side of the plate 10, near the outer end thereof, is formed a loop 12 in which is secured corresponding straps 13—14, there being a gag 15 in connection

with the straps to prevent their being pulled through the loop.

Upon the lower part of the anchor bar 1 is adjustably secured a hip rest consisting of a curved plate 16 that is lined upon its concave face with a pad 17.

Upon each side of the plate 16 is formed a corresponding loop 18 in which is secured straps 19—20 in the same manner as in the former instance. The plate has also a strap 21 through which the anchor bar 1 extends, and a thumb-screw 22 extends through the loop and has engagement in the bar for holding the hip rest in various adjusted positions on the bar.

Upon the top of the supporting bar 2, adjacent its inner end, is fixed a cradle 23 for the reception of the upper part of the patient's arm, and at the outer end of the supporting bar 2 is pivotally attached a pair of links 24 that have connection at their outer ends with a secondary supporting bar 25 upon which is fixed a cradle 26 for the forearm of the patient.

To the outer part of the supporting bar 2 is detachably secured, as an extension thereto, a bracket 27 in the outer upturned end of which is supported a hook 28 having upon its threaded shank a thumb-nut 29 by means of which the hook is adjustably positioned in the bracket.

In utilizing the appliance, the trunk rest is positioned against the body of the patient immediately beneath the armpit and is there held in place by securing the straps 13—14 about the body in the usual manner. The hip rest is vertically adjusted on the anchor bar so as to fit properly against the patient's hip, and is there held in place by securing the straps 19—20 about the body, as in the former instance. The cradle 26 is then adjustably positioned by manipulating its support 25 and the links 24 pivoted thereto so that the arm may be laid while bent at right angles at the elbow in the cradles 23 and 26. By applying tape in the customary manner about the arm and the cradles, the patient's arm is bandaged so as to be held fixedly in position accordingly as the appliance is adjusted. Also, by the use of tape,

in the manner familiar to surgeons, a connection is made between the patient's arm and the hook 28 so that as occasion arises a proper degree of tension may be applied to

the arm by manipulating the thumb-nut 29. As the arm is drawn outwardly, by the action of the hook the links swing accommodatingly upon their pivotal connections and 5 the cradle 26 becomes readjusted accordingly. In this manner an unnecessary bending of the patient's arm during the application of outward tension is obviated.

What I claim is:

- 10 1. A surgical splint including an anchor member provided with body rests; a supporting bar having a hinged connection with the anchor member; a threaded rod, one end of which is secured in said hinged connection; a toggle mechanism adjustable on said threaded rod and including opposed toggle arms connected respectively to said anchor member and supporting bar at points thereon spaced from said hinged connection; an 15 extension member including a bar having a splice connection with said supporting bar at the outer end thereof, and being disposed in alinement with said supporting bar; an adjustable hook at the outer end of said 20 extension member; a secondary supporting 25

bar having a link connection with said supporting bar at the juncture of said extension member therewith and extending at approximately right angles from said extension member and supporting bar; and a 30 cradle on said supporting bar and secondary supporting bar.

2. A surgical splint including an anchor member provided with body rests; a supporting bar having a hinged connection with 35 the anchor member; a threaded rod, one end of which is secured in said hinged connection; a toggle mechanism adjustable on said threaded rod and including opposed toggle arms connected respectively to said anchor 40 member and supporting bar at points thereon spaced from said hinged connection; a secondary supporting bar having adjustable connection with the former supporting bar at the outer end thereof; and a cradle on 45 each of said supporting bars.

In testimony whereof I affix my signature.

ROY D. FOULKE.
